(57) **CLAIM**

The ornamental design for artificial finger nail tip, as shown and described.

DESCRIPTION

FIG. 1 is a perspective view of artificial finger nail tip showing our design;

FIG. 2 is a front view thereof;

FIG. 3 is a rear view thereof;

FIG. 4 is a top plan view thereof;

FIG. 5 is a right side elevation view thereof, the left side elevation view thereof being a mirror image; and,

FIG. 6 is a bottom plan view thereof.

The broken line showing of a portion of a finger in FIG. 1 of the drawing is for illustrative purposes only and forms no part of the claimed design.
